UNITED STATES PATENT OFFICE.

EDWIN T. GREENFIELD, OF NEW YORK, N. Y.

JUNCTION-BOX.

SPECIFICATION forming part of Letters Patent No. 671,762, dated April 9, 1901.

Application filed March 2, 1901. Serial No. 49,564. (No model.)

To all whom it may concern:

Be it known that I, EDWIN T. GREENFIELD, a citizen of the United States, residing at New York, in the borough of Manhattan, county 5 and State of New York, have made a new and useful Invention in Junction-Boxes, of which the following is a specification.

My invention has for its objects, first, to provide a junction-box with inleading necks 10 or inlets which shall not offer any roughened or angular surface to the insulation of electrical conductors when drawn therethrough; and, second, to provide a junction-box with inleading necks or inlets which shall not offer 15 any roughened or angular surface to the insulation of electrical conductors when drawn therethrough, and also to provide means whereby the ends of tubular conduits may be secured thereto without screw-threading the 20 same.

Existing rules of the National Board of Fire Underwriters in the United States require 25 that in the wiring of buildings in which the wires are protected by interior or house conduits and metallic junction-boxes there shall be offered no abrading or tearing surfaces to the insulating-surfaces of conductors when drawn therethrough when placing the same in position. For the purpose of complying with 30 these rules it has heretofore been customary to insert bushings or sleeves in the necks or inlets of junction-boxes, the inner ends of which bushings are flared or of bell-mouth shape, said bushings being usually secured 35 in place by screw-threads in the inlets of the junction-boxes, or else provided with screw-threads at their exterior ends to which the conduit pipes or tubes are attached by corresponding screw-threads. My improvement is 40 designed to accomplish the same result by so constructing a junction-box that the before-mentioned bushings may be entirely eliminated and will be understood by referring to the accompanying drawings, in which—

Figure 1 is a plan view of a junction-box embodying my improvement, the cover of the junction-box being broken away at the lower left-hand corner for the purpose of more fully illustrating the same, two short sections of 45 conduit pipes or tubes being also illustrated in connection therewith. Fig. 2 is a sectional view taken on the broken line $\alpha\alpha$, Fig. 1, and

as seen looking thereat in the direction of the arrows from the bottom toward the top of the drawings, a part of the junction-box and one 55 of the conduit pipes or tubes being shown in elevational view.

Referring now to the drawings in detail, B 60 B' represent a metallic junction-box made, preferably, in two parts, provided with outwardly-extending half-necks N N N, the arrangement being such that when the two parts of the box are secured together by screws, as shown in Fig. 1, tubular inlets are provided 65 for the inner ends of the conduit pipes or tubes P P to be connected with the box, the structure being in this general respect not materially different from the junction-box disclosed in a prior patent, No. 665,676, granted to me on the 8th day of January, 1901. With 70 the present improvement, however, the inner surfaces of the half-necks N are flared or bell-mouthed, as shown at S, Fig. 1, so as to present a smooth non-abrading surface to the conductors as they are drawn through the 75 conduit pipes or tubes P and into the boxes. The exterior inner portion of the half-necks N are of larger bore, as shown at A, for the purpose of acting as a seat for the abutting ends of the conduit pipes or tubes P, this 80 bore being preferably of a diameter greater than the inner bore of the necks N, equal to the thickness of the metal of which the pipes or tubes P are composed, thereby offering an interior diameter of the tubes and the necks 85 which is continuous, and therefore offers no abrading - surface, as clearly illustrated in Fig. 2.

s are set-screws, one or more for each neck N, adapted to constitute means for securing 90 the ends of the conduit pipes or tubes P in position. With such an arrangement I avoid the necessity of threading the ends of the conduit pipes or tubes P at the time the wiring is being done in a building, thereby 95 saving very materially in expense and labor. It will also be further understood that with such an arrangement I am enabled to make the necks of the junction-boxes of lighter material than is possible with structures where 100 it becomes necessary to screw-thread them either exteriorly or interiorly, thereby making an important saving in material.

I have illustrated at the lower side of the

drawings in Fig. 1 how my improvement may be adapted for use in connection with flexible armored conduits like those disclosed in prior patents heretofore granted to me and 5 now largely in public use, T representing the enlarged screw-threads corresponding to the spiral screw-threaded armor of the before-mentioned flexible armored conduits.

I do not limit my invention to the especial 10 details of construction hereinbefore disclosed and illustrated in the accompanying drawings, as it might be departed from in numerous ways and still come within the scope of my claims hereinafter made. To illustrate, 15 instead of constructing the junction-boxes so that they and the necks of the inlets are made in two parts they might be constructed so that the entire necks are integral with a complete box, such junction-boxes being well 20 known and in general use.

Having thus described my invention, what I claim, and desire to secure by Letters Patent of the United States, is—

1. A junction-box provided with outwardly-extending necks integral with the box, the inner surfaces whereof are flared or bell-mouthed; in combination with means for securing conduit pipes or tubes thereto, substantially as described.
2. A junction-box provided with outwardly-extending necks integral with the box, the inner surfaces whereof are flared or bell-mouthed, the exterior inner portion of said necks being of larger diameter and adapted 30 to receive the ends of conduit pipes or tubes so that the inner surfaces of said conduit pipes

or tubes, when in position, shall be flush with the inner bore of the necks, substantially as described.

3. A junction-box provided with outwardly-extending necks integral with the box, the inner surfaces whereof are flared or bell-mouthed, the exterior inner portion of said necks being of larger diameter and adapted to receive the ends of conduit pipes or tubes 40 so that the inner surfaces of said conduit pipes or tubes, when in position, shall be flush with the inner bore of the necks; in combination with means for rigidly securing the conduit pipes or tubes and the necks together, substantially as described.

4. A junction-box constructed in two parts with half-necks flared or bell-mouthed at their inner ends and having an interior bore at their outer ends of increased diameter, substantially as described.

5. A junction-box constructed in two parts with half-necks flared or bell-mouthed at their inner ends and having an interior bore at their outer ends of increased diameter for receiving the ends of conduit pipes or tubes; in combination with means for firmly uniting the conduit pipes or tubes to the necks, substantially as described.

In testimony whereof I have signed my name to this specification in the presence of two subscribing witnesses.

EDWIN T. GREENFIELD.
